tion of Delaware

Application March 25, 1932, Serial No. 601,173

38 Claims. (Cl. 235—137)

This invention relates to computing mechanism in which computing wheels rotate in one direction for addition and in the opposite direction for subtraction, and also relates to a novel tens-carrying mechanism and novel means for preventing overthrow of the computing wheels. The invention is particularly applicable for modifying the well-known Underwood-Hanson computing machine for direct subtraction, thus greatly simplifying said machine, and for simplifying the tens-carrying mechanism and overthrow-preventing mechanism of said machine.

The Underwood-Hanson machine is described in the patent to O. Minton No. 1,280,065 dated September 24, 1918, which also discloses the Underwood subtraction mechanism, whereby subtraction is effected by adding the usual complement of the subtrahend.

Tens-carrying mechanism of the Underwood-Hanson machine is described in Patent No. 1,278,812 to H. Hanson, dated September 10, 1918.

According to the present invention, the subtraction-mechanism is much simplified in comparison with the Underwood subtraction mechanism described in the aforementioned patent to Minton No. 1,280,065. State-determining means are provided whereby the dial-wheels are caused to rotate in one direction for addition or to rotate reversely for subtraction. The subtraction is therefore "direct", as distinguished from subtraction effected by adding the complement of the subtrahend.

In the present invention, the register-bars having the computing wheel driving racks and the index-pins are retained. For addition the computing wheels are driven directly by said driving racks, whereas for subtraction the computing wheels are driven by intermediate rotation-reversing pinions or racks which may be permanently in mesh with the driving racks. The computing wheels are normally disengaged from both the driving racks and the intermediate pinions, and by the state-determining means are brought into mesh, either with the driving racks on the register-bars or with the intermediate pinions, during an initial portion of the advance movement of the general operator, depending on the setting of the state-determining means. Said state-determining means may be normally set or conditioned for addition so that normally the computing wheels will be directly driven by the driving racks on the register-bars. For subtraction said state-determining means may be conditioned as by the operation of a subtraction key to bring the computing wheels into engagement with the intermediate pinions.

The computing wheels remain in mesh throughout the rest of the advance movement of the general-operator cross-bar. Driving means for said general-operator cross-bar may be so ar-

ranged that at the end of said advance movement said general-operator cross-bar stands stationary for an interval of time to insure completion of the tens-carrying operation, as will hereinafter be made clear, the return movement of the general-operator cross-bar being commenced at the end of said interval. In the initial portion of said return movement, the computing wheels are caused to be disengaged before the general-operator cross-bar picks up the advanced register-bars to restore them to their normal positions. By thus disengaging the computing wheels, before the return of the register-bars, the necessity for providing one-way connections of the computing wheels to the register-bars is avoided, with consequent simplification of the mechanism.

The carrying of tens from one computing wheel to another computing wheel of the next higher denomination involves the release of a spring-pressed normally latched register-bar stop through the movement of said first computing wheel past its carrying position. The register-bar stop in its normal unreleased position is effective to limit the movement of the register-bar for the computing wheel of next higher denomination, to the end that said register-bar may not be overthrown while being driven forward by the general-operator cross-bar. When said register-bar stop is released from its latch, and is, in consequence, caused to be withdrawn by its spring, the register-bar is permitted to advance an extra unit space to thereby carry over a tens value, said stop being still effective, however, to prevent overthrow of the register-bar, since it is only withdrawn enough to permit said extra advance.

If a register-bar stop be released and withdrawn before the general operator reaches the end of its advance movement, the register-bar which said stop controls is, according to an important feature of the invention, advanced positively for "carrying", by the movement of the general-operator cross-bar as it completes its advance stroke. To this end, the general-operator cross-bar does not engage the index-pins directly for advancing the register-bars, but there are interposed ahead of said cross-bar for engaging the index-pins, the ends of a series of levers of the first order pivoted on a fulcrum-rod carried by the general-operator cross-bar. The other and normally free ends of said levers are, in the direction of cross-bar movement, opposite the free ends of a series of similar levers of the first order pivoted on a fixed fulcrum-rod, the other ends of said latter levers being connected to the aforesaid register-bar stops. The levers connected to said stops are capable of two positions, depending on whether or not the stop is withdrawn for carrying. If a stop is not withdrawn for carrying, the free end of the lever con-

nected thereto just meets the free end of the opposite lever on the fully-advanced general-operator cross-bar. The two levers thus meeting form a pincer-like arrangement wherein the index-pin 5 is held between the register-bar stop and the opposite end of the lever on said cross-bar, said cross-bar backing up said opposite lever end. Thus the advanced position of the register-bar is secured against overthrow and also against 10 rebound. Should a register-bar stop be withdrawn before the general-operator cross-bar reaches the end of its advance movement, the free end of the lever connected to said register-bar stop will be moved toward the free end of the opposite lever 15 on the approaching cross-bar and thus constitutes an interponent which will engage and arrest said free end of the cross-bar lever just before the cross-bar completes its advance movement.

It will be understood now that as said cross- 20 bar advance movement is completed, the lever on the cross-bar will be rocked because of the arrest of its free end, thereby causing an extra tens-carrying advance of the register-bar, the extra advance being positive due to the positively driven 25 cross-bar. The levers may be so proportioned that when a sufficient extent of carrying advance is reached, the index-pin is again held between the register-bar stop and the opposite end of the lever on the cross-bar to prevent overthrow or 30 rebound of the register-bar. The free ends of the two series of levers may be proportioned and arranged so that the levers connected to the register-bar stops may lock the levers on the cross-bar against reverse movement at the end 35 of a carrying movement of said cross-bar levers. Such proportioning and arrangement of said free ends are also effective to stabilize the levers connected to the register-bar stops as their free inter-ponent ends co-operate to rock the cross-bar levers, inasmuch as the lines of reaction, which 40 the free ends of said stop-levers afford to rock the cross-bar levers and lock the same against reverse rotation, may in either case pass through the fulcrum center of said stop-levers.

If, as may happen in some computations, a 45 register-bar stop be released and withdrawn for carrying a tens value after the general-operator cross-bar has completed its advance movement, the carrying advance of the register-bar controlled by said stop may be effected by power derived from suitable springs connected either to the register-bar stop or its lever. In this case it 50 will be understood that the free ends of the stop-lever and the opposite cross-bar lever just meet 55 as the cross-bar completes its advance and that a subsequent release and withdrawal of the stop will cause the lever connected therewith to be rocked by the power of the aforesaid spring, with a consequent rocking of the lever on the cross-bar and a consequent carrying advance of the 60 register-bar whose set index-pin is held between the register-bar stop and cross-bar lever as aforesaid.

It will be seen now that the cross-bar levers, 65 broadly considered, constitute rack-engaging fingers, which, in respect to said cross-bar or any other suitable movable member on which they may be mounted, may be advanced one unit-space, thus enabling said cross-bar or movable 70 member which has a fixed extent of movement to advance the racks an extra unit-space for carrying. It will also be seen that the advance of said fingers in respect to the cross-bar, and hence the "carrying" of the register-bars, are in most 75 cases accomplished positively.

In practicing the invention the register-bar stops may be in the form of elongate bars connected at one of their ends to their respective levers, said ends also forming the stop or abutment between which and the cross-bar lever or 5 finger, the index-pin is held at the end of the register-bar movement. Said stop-bars, viewed sidewise of the register-bars, may extend substantially parallel to the latter and may be latched at their other ends over a latching bar. Each 10 computing wheel may have the usual carrying tooth. Said tooth, in the preferred form of the invention, does not, for "carrying" as aforesaid, release the corresponding register-bar stop by direct engagement, but instead, for convenience 15 of arrangement of the parts, releases said stop through an intermediate carrying lever, one end of which may be engaged by said carrying tooth, and the other end of which may engage the stop to displace the same from the latching bar. The 20 tooth-actuated carrying levers may be mounted in the aforesaid frame, in which the computing wheels are mounted, and may be so arranged that the ends which engage the stops may properly engage said ends irrespective of the shifting 25 of said frame either toward the register-bar racks or toward the intermediate racks.

This application is in part a continuation of my co-pending application Serial No. 324,353, filed December 7, 1928 (now Patent No. 1,927,951, dated 30 September 26, 1933).

Other features and advantages will hereinafter appear.

In the accompanying drawings,

Figure 1 is a cross-section through the combined typewriting and computing machine, showing, in side elevation, details of the novel carrying mechanism.

Figure 2 is a side elevation, showing details of one form of power-drive for the computing mechanism.

Figure 3 is a detail view, showing the construction of means whereby a universal bar for restoring the carrying stops is operated.

Figure 4 is a top plan view, looking down on the computing mechanism, to show the arrangement of four registers, and the operating parts for said registers.

Figure 5 is a skeleton view, showing, in perspective, the arrangement of said four registers, 50 and the arrangement of a register-bar, relatively to the novel carrying means, and also bringing out other details of construction.

Figure 6 is a skeleton view, showing, in perspective, the fixed plates within which a register-wheel frame is shifted, and also showing, in detail, means for ensuring relatching of carrying stops.

Figure 7 is a view, showing, in perspective, details of operating connections associated with the latching bar for the carrying stops.

Figure 8 is a detail front view, showing how said latching bar is supported in the aforesaid fixed plates.

Figure 9 is a side view, illustrating means and the operation thereof for shifting the aforesaid latching bar.

Figures 10 and 11 are enlarged side views, showing details of the novel carrying mechanism, Figure 10 showing said mechanism in normal position, and Figure 11 showing said mechanism operated to effect the "carrying" of a number.

Figures 12, 13 and 14 are each a side view of a register-bar and the train of carrying parts extending from one computing wheel to the register-bar of next higher denomination. Figure 12 75

shows a computing wheel directly engaged with the register-bar for addition; and also shows a register-bar in advanced position without having carried. Figure 13 is similar to Figure 12, but 5 shows the register-bar advanced for carrying. Figure 14 shows a computing wheel not directly connected to the register-bar rack, but connected thereto by the intermediate pinion to reverse the rotation of said wheel for subtraction, Figure 14 10 also showing the register-bar advanced for carrying, and, compared with Figure 13, showing that the carrying advance of a register-bar is the same for subtraction as it is for addition.

Figures 15 and 16 are partial plan views of 15 means forming the power-drive shown in Figure 2.

As seen in Figure 1, the novel computing mechanism co-operates with a typewriter in which numeral-keys 10 mounted on key-levers 11 may, 20 through other members of the usual type-action, cause types 12 to print against a platen 13. Said platen 13 is in a carriage 14 traveling on rails 15 and 16 of the typewriter-framework 17. By 25 operation of the type-keys said carriage is propelled in letter-feeding steps determined by an escapement-mechanism 18 under control of said keys and spring-motor 19.

The computing mechanism may include one or 30 more sets of computing wheels 20, Figure 4, indicating four sets of computing wheels. For each computing wheel there is a register-bar 21 carrying a series of downwardly-settable index-pins 22, for the digits from "0" to "9". As disclosed in my co-pending application, Serial No. 82,226, 35 filed January 19, 1926, (now Patent No. 1,869,582, dated August 2, 1932) only one pin at a time may be set in a bar, the setting of one pin in a register-bar being effective to force any previously-set pin in said bar back to its normal position by means 40 represented by cam-blocks not shown, interposed between the stop-pins and fully described in said co-pending application No. 82,226, the cam-blocks, briefly explained, being displaced longitudinally of the register-bar upon depression of any pin, and by reason of their cam-formations 45 being capable of restoring a previously-set pin as they are displaced. The "0" pin in each register-bar is normally set, and is, of course, restored by the setting of any higher pin in a register-bar. 50 For setting an index-pin in any register-bar, each numeral-key lever 11 has depending therefrom a stem 24, to rock a shaft 25, each key-lever having its own shaft. The several shafts 25 are for actuating parallel motion pin-setting linkages 55 26, one for each numeral-key. Each linkage includes a pin-setting bar 27 movable edgewise and downwardly upon operation of said linkage by its numeral-key.

The pin-setting linkages are of the type shown 60 in the aforementioned patents to Minton and Hanson. Each pin-setting bar 27 is connected at each end to a horizontal arm of a bell-crank, not shown, vertical arms of said bell-cranks being connected to the ends of an upper bar 28. Arms 65 29 connect the rock-shafts 25 to the upper bars 28 of their respective linkages, each shaft also having fast to its end a horizontally-extended arm 30 engageable by the numeral-key stem 24.

Index-pins are set in the register-bars as the 70 carriage moves predetermined zones of a work-sheet past the printing point. As indicated in Figure 1, downward movement of a pin-setting bar 27 is ineffective to set a pin in a register-bar unless the bar is slightly advanced to bring the 75 pins therein under the pin-setting bars 27. This

advance is accomplished seriatim for the several register-bars by the movement of the typewriter-carriage 14 in presenting the aforesaid work-sheet zones to the printing point. To this end, said carriage may carry tappets 31 settable along rails 5 32 of said carriage according to the location of zones of carriage travel in which index-pins are to be set. By the step-by-step movement of the typewriter-carriage 14 in such zone, a tappet displaces, in seriatim order, the ends 34 of jacks 35, 10 and thereby depresses push-rods 36, to rock levers 37, each lever having one arm 38 connected to a push-rod as shown, and another arm 39 connected to one end of a transposing linkage 40, the other end of said linkage 40 pushing upon a pin 41 15 projecting from the side of a corresponding register-bar. According to the usual practice, the tappets 31 are offset from one another, see Figure 1, each tappet being mounted on a dog 33. By such offsetting one tappet is effective on only one 20 set of jacks 35 and ineffective on other sets of jacks 35, according to which set or sets of register-bars 21 shall be indexed.

With the typewriter-carriage 14 in a computing zone, a push-rod 36, corresponding to the column 25 of the work-sheet zone which is at the printing point, will have been depressed by means of the tappet 31, and the register-bar 21 connected thereto will be advanced, so that its index-pins 22 are under the pin-setting bars 27. Operation of 30 a numeral-key now will cause the corresponding pin-setting bar 27 to descend and set a corresponding index-pin 22. The carriage 14 then escapes, releasing said push-rod 36 and causing the corresponding register-bar to be retracted by 35 means of a spring-device 42. In the meanwhile, the push-rod 36 for the next column will have been depressed as the carriage took its letter-feeding step and the next register-bar will have been advanced to bring its index-pins under the 40 pin-setting bars. In this manner is the pin-setting accomplished seriatim for the register-bars as the carriage moves a computing zone of the work-sheet, column by column, past the 45 printing point.

The transposing linkages 40 transpose the seriatim order, in letter-feeding direction, of push-rod operation into the proper but reverse order of the seriatim indexing of the register-bars, each linkage 40 including a bell-crank 40^a 50 which engages the pin 41.

The index-pins 22 are set into the path of register-bar-engaging fingers 43 formed at the upper ends of levers 44, carried by a cross-bar 45 movable forward and back for advancing the 55 register-bars and returning the advanced bars. The purpose of said levers, which is to provide for extra carrying advance of the register-bars, and the co-operating parts, will be explained further on.

For moving the cross-bar 45 in the direction in which it is to advance and return the register-bars 21, there are employed the usual racks 46 guided for reciprocating endwise movement along the inner sides of side members 47 of the 60 computing-mechanism framework. Said racks 46 carry plates 48 provided with slots 49 in which tenons 50 at the ends of said cross-bar are inserted. Said slots 49 are longer than is the width of said tenons, so that the cross-bar may 65 slide edgewise in said slots for a purpose to be explained. By moving both racks 46 in unison, the cross-bar 45 may be moved without skewing, and, to this end, said racks are coupled by a cross-shaft 52 journaled in said framework side 70 75

members 47, and having gear-sectors 53 fastened thereto, one at each end of said shaft, aligned with said racks 46, see Figure 4. Said gear-sectors are not directly connected to the racks, but 5 are connected thereto by intermediate pinions 54, mounted on the side members 47, to give the racks 46 the right direction of movement in respect to reciprocatory rotation of the cross-shaft 52, which may have connected thereto an 10 operating handle (not shown), for hand operation of the computing mechanism. For operation by power, there may be used the power-drive shown in the patent to F. A. Hart, No. 1,171,403, dated February 8, 1916, said mechanism presenting 15 a driver 55, which, driven by a crank (not shown), reciprocates forth and back in the direction of movement of the racks 46 and register-bars 21. Connection between said driver 55 and the racks 46 is made by means of the usual member 56, which embraces said driver, as seen in Figure 1, and which is fastened to the under side of the left-hand rack 46, said driver being positioned sidewise of the machine to align with said left-hand rack 46. For disengaging the 20 power-drive, the casing 51, from which the driver 55 projects, may be lowered in the usual manner, to thereby withdraw said driver 55 from the member 56. When the driver 55 is thus withdrawn, the computing mechanism may be hand 25 operated by means of the aforesaid handle (not shown).

By means of the usual key-operated clutch not shown herein, but shown in said Hart patent, the driver 55 is normally disconnected from the 30 motor-drive and is stationary in the position shown in Figure 1. By means of said clutch and its controlling key, the driver is connected to the motor-drive long enough to impart just one forth-and-back movement to said driver and 35 hence to the cross-bar 45.

When the cross-bar 45 has advanced and carried the register-bars 21 forward, to extents determined by whichever digit-pins 22 were set, in the several register-bars, there must be a suitable period of time during which certain carrying operations may take place, as will hereinafter be explained. That is, said cross-bar 45 must not immediately start its return movement after completing its advance movement, because such 40 immediate return movement would in some cases return certain register-bars 21 before they had time to "carry". To hold the cross-bar 45 stationary for a sufficiently long carrying period, the last portion of the forward stroke of the driver 45 and an initial portion of the return stroke of said driver are rendered ineffective to move the cross-bar 45, said driver 55 moving forth and back as usual, but the time-period of said portions of its strokes being apportioned to said 50 carrying operations. It is to this end that said cross-bar is movable edgewise in its retaining slots 49 of the rack-plates 48, it being understood that said plates 48 will move with the driver 55 throughout the full range of movement of said driver, and that the cross-bar 45 alone is held stationary just before and just after said driver 55 completes its forward stroke. For thus holding said cross-bar 45 stationary, there may be mounted and fastened on each framework side 55 member 47 a plate 51, in which is formed a cam-slot 58, the plates being disposed, as best seen in Figure 4, between the racks 46 and the walls of the side member 47. On each rack 46 there is pivoted at 59 on a suitable stud, as shown, a bell-crank lever 60, having a horizontal arm 61 for 60

engaging the cam-slot 58 and an upright arm 62 connected to the cross-bar 45 by a link 63, the latter having a pivotal connection 64 to said arm 62. The horizontal arm 61 carries a roll 65 for engaging the cam-slot 58. The arms 61, 62 of 5 said lever are on opposite sides of the rack 46 and are joined by a cross-piece 66 (Figure 4), forming part of said lever 60. The link 63 is attached at one end to the cross-bar by screws 67, there being provided sufficient play between the sides of the 10 slot 49 and the tenon 59 to avoid binding between said tenon and slot as the lever 60 rocks.

The range of forth-and-back movement of the driver 55 may, as in the case herein illustrated, be just enough for full advance and return of the 15 register-bars 21. In such case, if the aforesaid portions of driver-movement preceding and following its most advanced position are rendered ineffective to move the cross-bar 45, so that there may be afforded time for carrying, it follows 20 that said cross-bar 45 must in some other manner still receive the same extent of movement as the driving member 55. To compensate for the idle portion of the forward movement of the driver 55, the cam-slot 58 is sloped downwardly at 68. This downward slope through the medium of the lever 60 causes an advance of the cross-bar 45, relatively to the racks 46 and plates 48, sufficient to compensate for the movement lost through the idle portion of the forward stroke 25 of the driver 55. When said driver starts its idle portion of stroke, it is rendered ineffective to further advance the cross-bar 45. This is accomplished by a reverse movement of the lever 60, the cam-slot 58, to this end, including an upturned portion 70, so formed that the cross-bar 45 is held stationary because of the reverse movement imparted to the lever 60 by said upturned portion 70 while the driver 55 completes its forward stroke. As the driver 55 thus completes 30 its forward stroke, the roll 65 will have reached the position shown in full lines in Figure 11. The broken lines, indicating the roll 65 and the driver 55, indicate, with reference to the full-line positions of said roll and driver, some measure of the idle part of the stroke of said driver 35 55. It will be evident that at the beginning of the return stroke of said driver 55, there is also an idle portion in which the cross-bar 45 is not moved while the roll 65 rides down the cam-slot 40 portion 70 with consequent rotation of the lever 60. Also, in said return movement of the driver 55, the cam-slot portion at 68 will be effective 45 to extend the return movement of the cross-bar 45 sufficiently by means of said lever 60 to fully 50 restore the register-bars 21. The cross-bar 45 in its fully returned position may abut stops 68a, 55 Figures 4, 10 and 11.

Another form of cross-bar-driving mechanism is indicated in Figures 2, 15, and 16. In this latter form, the revolution of a roller 73, driven in a circle by a motor 74, is translated into reciprocatory movement of the cross-bar 45 by means of a link 75 fastened to said cross-bar and projecting rearwardly therefrom. The link 75 has at its rear end a head 76 forming a face 77 which the roller 73, revolving in the direction of the arrow, Figure 15, may engage to push the link 75 forwardly, said roller 73 in its initial position being as indicated in Figure 16. When the revolution of the roller 73 has advanced the link 75 sufficiently, said roller idly passes a curved portion 78 of the face 77, said curved portion 78 being at this time concentric with a stud 79 about which said roller 73 revolves on a plate 80. 75

The period of this idle movement of the roller 13 before it begins to retract the link 75 and cross-bar 45 is utilized to insure in this form of drive the completion of "carrying operations", 5 already mentioned. The cross-bar 45 is, where this form of power-drive is employed, fixed in the plates, designated in Figures 2 and 15 by reference numbers 48^a, no movement of said cross-bar relative to said plates being required.

10 As seen in Figure 15, the curved portion 18 is preferably so designed that the idle movement of the roller 13 may be about evenly apportioned on either side of the extreme forward position which said roller reaches, the length of 15 said curved portion 18 depending on the time interval to be allowed for "carrying" before retraction of the link 75 is commenced. Figure 15 indicates by the broken circle at the right the position of the roller 13 at that point of its 20 revolution about the stud 79 where it commences the return of the link 75. For returning the link 75 the roller 13 reacts against a face 82 of said link. Inasmuch as the roller 13 in that part of its revolution in which it moves forward can 25 have no effect on said face 82, the latter does not extend beyond the position from which said roller begins its forward movement. Moreover, by thus limiting the extent of the face 82, it is feasible to move the cross-bar 45 forwardly 30 independently of said roller, as in hand-operation, in which case the normal position of the roller may be as indicated in Figure 16. The face 82 may for a portion of its length be concentric with the curved portion 18 of the face 35 77, thereby giving acceleration to the final part of the return movement of the link 75 and keeping the roller 13 in contact with the face 77-18.

The roller 13 revolves only when the register-bars 21 are to be advanced for the accumulation 40 of a number and returned, and is, to this end, connectible to the motor 14 by a clutch (not shown) such as is shown in the aforesaid patent to F. A. Hart, which clutch with reduction gearing 83 may be enclosed in a casing 84 extending 45 from the motor 14 and which may carry the aforesaid stud 79 around which the roller 13 revolves and which stud is spaced from the driven clutch-shaft 85, for arrangement of the parts as indicated. Said shaft 85 may be connected to the 50 roller-carrying plate 80 by a pinion 86, fast to the shaft 85, and a meshing pinion 87, fast to the plate 80. The motor 14 may be supported on a base 68 of the computing machine.

Each computing wheel 20 has fastened thereto 55 a pinion 89. As seen in Figure 12, the pinions 89 may mesh with racks 90 formed at the forward ends of the pin-bars 21, or, as seen in Figure 14, the pinions may be driven by said racks 90 through intermediate pinions 91, which may be 60 permanently in mesh with the racks 90. As indicated in Figures 1 and 10, the computing-wheel pinions, and hence the computing wheels, are normally disengaged from both the pin-bar racks 90 and the intermediate pinions 91. Direct engagement of the computing wheels with the racks 90 causes them to revolve clockwise during a forward movement of the pin-bars 21. On the other hand, if the computing wheels be driven through the intermediate pinions 91, during said 65 forward movement of the pin-bars 21, their rotation will be counterclockwise. One direction of rotation of the computing wheels may be for addition, and the opposite direction may be for subtraction. According to the arrangement of 70 the dial-wheel numbers, as herein indicated, the

clockwise rotation of the computing wheels, when directly driven by the racks 90, corresponds to addition, and the counterclockwise rotation of the wheels, when driven through the intermediate pinions 91, corresponds to subtraction. 5

To shift the computing wheels 20 either downwardly for engagement with the register-bar racks 90, or rearwardly for engagement with the intermediate pinions 91, said wheels 20, independently rotatable on a spindle 92, are retained with said spindle in a shiftable frame 93 having side plates 94 spaced apart so that the ends of said spindle 92 may be journaled therein. Said side plates 94 may be spaced apart by a cross-member 95, and by the spacing afforded by the series of computing wheels and the hubs or collars 96 adjacent to the outer computing wheels. The computing-wheel frame 93 is held against lateral displacement between fixed plates 97, which may be secured to, and project upwardly from, a front cross-member 98 of the computing-mechanism framework, said cross-member 98 serving with a rear cross-member 99 to space apart the aforesaid side members 47 of said framework. 10 15 20 25

For supporting the computing-wheel frame 93 between said fixed plates 97, so that it may be shifted, there may be used a cross-rod 100 supported by and spanning said plates 97. Slots 101 at the rear end portions of the computing-wheel-frame plates 94 embrace said cross-rod, and when the computing-wheel frame is in normal position, in which the computing wheels 20 are disengaged, said slots 101 extend in a horizontal direction. The forward portion of the computing-wheel frame may be supported on arms 102 projecting from a rock-shaft 103, each computing-wheel frame being provided with one of said arms, as shown in Figure 4. Each arm 102 has a slot 104 which, when the frame 93 is in normal position and the computing wheels are disengaged, extends in a horizontal direction. Said slot 104 embraces the cross-member 95 of the computing-wheel frame. 30 35 40 45

From Figure 1 it will be seen that the slots 101 and 104 guide the frame for rearward and forward shifting, the rearward shifting being effective to engage the computing wheels with the intermediate pinions 91, the forward shifting of said frame conversely disengaging the computing wheels from said intermediate pinions 91. Figure 14 indicates the computing wheels engaged with said intermediate pinions. 50

From Figures 1 and 11 it will also be seen that the frame 93 may turn about the cross-rod 100 as a fulcrum, such turning being effected by rocking the shaft 103. In this case the computing wheels 20 will be directly engaged with the pin-bar racks 90, as indicated in Figures 11, 12 and 13. 55 60

Preparatory to the forward movement of the register-bars 21, the computing wheels are brought into engagement with either the register-bar racks 90 or the intermediate pinions 91, and similarly, preparatory to the return movement of the register-bars, the computing wheels are disengaged again so as not to be reversed by the return movement of said register-bars. 65

Selective connections (not shown), for coupling the driving mechanism of the computing machine to the rock-shaft 103 or to a link 106 may be provided for effecting shifting of the computing-wheel frames 93 at the proper times during a computing-machine cycle. The rock-shaft 70

103 may be split into individual rock-shafts, one for each of the registers, to control the registers independently, or there may be one rock-shaft common to all the registers, and it will be understood that said selective connections may be made accordingly. Such selective connections predetermine whether the computing-wheel pinions 89 are to be presented directly to the racks 90 as for addition, or whether they are to be presented to the intermediate pinions 91 as for subtraction. The fixed plates 97 may have two-way slots 107, into which the computing-wheel spindles 82 may extend, so that their ends may receive screws 97^a, whose heads bearing against the outer surfaces of said plates 97 serve to retain said spindles endwise. Horizontal and vertical branches of said two-way slots 107 serve to hold the frames 93 against displacement transversely of said branches.

20 As already stated, the levers 44 on the general-operator cross-bar have register-bar-engaging fingers 43 for pushing the register-bars forward. How said levers 44 and their register-bar-engaging fingers operate to advance the register-bars 21 extra unit-spaces for carrying, will now be explained. Said levers 44, of which there is one for every register-bar, may be mounted on a common fulcrum-rod 108, and there may be one such fulcrum-rod for every set of register-bars 30 of the computing mechanism retained between ears 109 of a bracket 110 secured to the cross-bar 45, said ears projecting downwardly and forwardly from said cross-bar. The levers 44, individually rockable on their fulcrum-rods, are spaced apart and located, as by collars or hubs 111, Figure 4. The register-bar-engaging fingers 43 of said levers 44 are aligned with the pins 22 of their respective register-bars, and may be formed by tabs bent at right angles to said levers.

The carrying of a tens value from one computing wheel to a wheel of next higher denomination is, according to the present invention, effected by advancing the register-bar for said higher wheel 45 an extra unit-space, the extra advance being effected by causing the lever 44 to be rocked counterclockwise from the position seen in Figure 12 to the position seen in Figures 11, 13 or 14. As seen in Figures 10 and 12, a register-bar-engaging finger 43, backed by the cross-bar 45, may advance a register-bar by engaging a depressed pin 22. The advance of the cross-bar 45 and hence of the fingers 43 thereon, when abutting the forward side of said cross-bar, is always to the same extent, and the extent of advance of a register-bar therefore depends upon which index-pin is depressed. If the "0" pin, which is the first pin from the front of the machine, is not displaced from its normally-depressed position by the setting of a higher pin, the register-bar will not be advanced, because the position which the cross-bar, with the corresponding finger 43 bearing thereagainst, reaches at the end of its advance 60 movement is such that said finger 43 just touches the depressed "0" pin. If a "1" pin is depressed, the register-bar will be advanced until said "1" pin is in the position from which the "0" pin moved in such advance of the register-bar. Similarly, by depression of a higher pin, the register-bar will be advanced until said higher pin is in the position which the "0" pin left in said advance.

Thus, it will be seen that, irrespective of the 75 value of the depressed pin 22, the depressed pin

always reaches the same position, and that it is therefore feasible to provide stops which will prevent overthrow of the register-bars as they reach the ends of their respective advance movements, and that said stops will be effective for any extent of said advance movements as determined by the values of the depressed pins 22. A stop 112 for each register-bar is therefore provided and is caused to abut the forward side of the depressed pin as a register-bar carrying said pin reaches the end of its advance position.

Two conditions govern the application of the stops 112, one condition being that said stops must be individually shiftable to permit an extra carrying advance of their respective register-bars, the other condition being that said stops, when the computing mechanism is in its normal condition, that is to say, when the register-bars are not being advanced to accumulate a number, must be sufficiently removed from the normally depressed "0" pins to permit the aforesaid slight advance of the register-bars seriatim during the indexing of the register-bars.

To these ends, the register-bar stops 112 may be formed on the rear ends of elongate bars 113, which are to be shiftable simultaneously from a normal position, indicated in Figure 1, wherein the stops 112 are far enough removed from the depressed "0" pins, as seen in Figure 1, to permit the aforesaid seriatim advance of the register-bars, to the position indicated in Figure 12, and more clearly indicated in Figure 10 by the dot-and-dash outline of a stop 112, in which latter position the stops 112 may abut the depressed pins of the advanced register-bars or the "0" pins of the register-bars that are not advanced. From said latter position, the bars 113, and hence the stops 112, are to be individually movable in a forward direction to permit an extra carrying advance of the corresponding register-bars, the forward carrying movement of the bars 113 being limited, however, so that the stops 112 are also effective to prevent overthrow of the register-bars when said register-bars carry. The forward carrying movement of any bar 113 is also utilized to effect, as will be explained, a carrying displacement of the corresponding lever 44 and its register-bar-engaging finger 43.

To these ends, the bars 113 are urged forwardly by individual springs 114, but are normally latched in non-carrying positions over a transverse latch-bar 115, each bar 113 having a latching edge 116, which normally abuts the rearward edge of said bar 115. The several bars 113 are pivotally connected at their rearward ends to upstanding arms 117 of levers 118 of the first order individually rockable on a fixed fulcrum-rod 119. Arms 120 of said levers 118 extend, in the normal positions of said levers as seen in Figure 1, downwardly and rearwardly. To effect rearward movement of all the bars 113 to bring the stops 112 from the positions seen in Figure 1 to the position seen in Figure 10 or 12, in which latter position the stops are effective to prevent overthrow of the register-bars, the latch-bar 115, together with all the bars 113 latched thereto, is advanced rearwardly during the advance movement of the cross-bar 45 as will later on be explained. As the bars 113 are so moved simultaneously, their levers 118, mounted on the fixed fulcrum-rod 119, are rotated clockwise, so that the arms 120 of said levers 118 are shifted from the position indicated in Figure 1 to the position indicated in Figure 12. Said latter position of

the arms 120 is such that pins 121 therein just abut downwardly-extending arms 122 of the corresponding levers 44 on the cross-bar 45 when the corresponding register-bars register a non-carrying advance, as indicated in Figure 12. From Figure 12 it will be seen that, with the arm 122 abutting the pin 121 and the register-bar-engaging finger 43 abutting the cross-bar 45, and the bar 113 latched over the bar 115, a register-bar whose depressed pin 22 is closely confined between the stop 112 and finger 43 is secured not only against overthrow, but is also secured against rebound.

Referring to Figures 10 and 11, it will be further seen that upward displacement of the forward end of one of the bars 113 will cause said bar to move forwardly under the pull of the spring 114.

As a bar 113 thus released from the latch-bar 115 moves forwardly, it rocks its lever 118 counterclockwise to the position seen in Figures 11, 13 and 14, and which position may be determined as by abutment of the lever 118 against a transverse rod 123 supported by and spanning the fixed plates 97 of each register. It will be evident that a lever 118, thus rocked counterclockwise by release of its bar 113, will also cause the corresponding lever 44 on the cross-bar 45 to be rocked counterclockwise, thereby causing the register-bar-engaging finger 43 on said lever 44, and hence the corresponding register-bar itself, to be advanced in respect to said cross-bar 45. Thus each register-bar may receive an extra movement depending upon the release of a bar 113. To prevent the levers 44 from falling into a disabling position when not engaging an index-pin 22, as, for example, when the cross-bar 45 is fully returned, each lever 44 may have an arm 124 to limit its counterclockwise movement, as is indicated, Figure 11, by the abutment of said arm with the bracket 110 attached to said cross-bar 45.

The release of a bar 113, as aforesaid, is to be effected every time a computing wheel, of next lower order to the register-bar controlled by said bar 113, passes its carrying point, and each computing wheel has therefore, projecting from its periphery, a carrying tooth 125. On account of the different positions of the computing wheels in addition and subtraction, the carrying teeth 125 of the several wheels operate to release the bars 113, preferably through intermediate carrying levers 126 individually rockable on a fulcrum-rod 127 supported between the side plates 94 of the computing-wheel shift-frame 93, and spaced and located on said rod 127 as by collars or hubs 128, Figure 11. Each carrying lever 126 has a cam-shaped arm 129 arranged so that said carrying lever may be rocked by the carrying tooth 125 in either direction of rotation of the computing wheel. As a carrying lever 126 is rocked, the end of an arm 130 thereof moves upwardly against and displaces the forward end of a corresponding bar 113, and thus releases said bar 113 from the latch-bar 115.

The location of the ends of the arms 130 of the levers 126 is so arranged with respect to the cross-rod 100 that said ends of the arms 130 describe an arc or line when the computing-wheel shift-frame 93 is swung around said cross-rod 100 for engaging the computing wheels directly with the register-bar racks 90, which is substantially the same as the line along which said ends 75 of the arms 130 move as the computing wheels

are shifted rearwardly with said frame 93 for engagement with the intermediate pinions. Thus the carrying levers 126 are effective in either adding or subtracting position of the computing wheels 20, to release their respective bars 113. 5

A carrying train from any computing wheel to the register-bar of the computing wheel of next higher denomination includes the carrying lever 126 actuated by the former computing wheel, the bar 113, releasable by said carrying lever 126, the lever 118, connected to the rear end of said bar 113, and the lever 44, controlled by the latter lever 118, the register-bar engaging finger 43 of said lever 44 being aligned with the pins 22 of the register-bar of the computing wheel of said next higher denomination. Thus, one end of said train is the arm 129 of the carrying lever 126, and is adjacent the computing wheel of lower denomination, and the other end of said train is the register-bar-engaging finger 43 for the register-bar of next higher denomination. The required offset of said ends of the train may be effected by forming and arranging the parts thereof as indicated in Figures 4 and 5. As indicated in Figure 5, the carrying lever 126 may be within the plane of rotation of the carrying tooth 125. The forward portion of the bar 113 is aligned with said lever 126, the rear portion of said bar being offset to the left by bends 132 and having the stop 112 formed by a tab bent to the left to align with the pins 22 of the register-bar of next higher denomination. The lever 118 is pivoted on the left side of said bar 113 and its pin 121 projects to the left to align with the arm 122 of the lever 44 for said register-bar. Said lever 44 has its finger 43 in the form of a tab bent as shown to align with said pins 22 of said register-bar. 15

Each bar 113 is connected to its lever 118 by a headed pivot-stud 133. The levers 118, individually rockable on their fulcrum-rod 119, may be spaced and located on said rod as by hubs or collars 134, each register having one of said rods which is supported by and spans the fixed plates 97. Although the units register-bar never carries, it is nevertheless provided with a bar 113, a lever 118 and a lever 44, the latter having its register-bar-engaging finger 43, inasmuch as these parts also prevent overthrow and rebound of the units register-bar. No carrying train extends from the computing wheel of highest denomination, which is the first wheel from the left of the register. 20

In most cases, the levers 44 are rocked positively by the positively-driven movement of the cross-bar 45 itself when carrying is to be effected and therefore an extra carrying advance of a register-bar is effected positively. That is to say, in most cases carrying bars 113 will have been released, and the levers 118, connected thereto, will have been rocked before the cross-bar 45, with its register-bar-engaging levers 44, effects contact of the arms 122 of said latter levers with the pins 121 of the arms 120 of 60 levers 118. Thus, said arms 120 and their pins 121 form interponents which, by the release of their respective bars 113, are thrust into the path of the advancing cross-bar levers 44 on the cross-bar 45. It will be seen, therefore, that as 65 the arms 122 of the cross-bar levers encounter the pins 121, thus thrust into said path, the cross-bar levers 44 will be caused to rotate counterclockwise to an extent equivalent to advancing their register-bars an extra unit-space, and which 70 75

extent, it will be understood, may be determined by suitable proportioning and arrangement of the parts as illustrated in the drawings. In those cases where a carrying advance of a register-bar 5 is effected, after said register-bar has reached its advanced position, as indicated in Figure 12, the necessary carrying displacement of the parts involved is effected by the power afforded by the spring 114.

10 The lever 118, whose arm 120 is thus thrust into the path of the advancing cross-bar lever 44, is to be stabilized against counter-rotation while it co-operates to rock said cross-bar lever 44, and the later lever 44 is also to be locked 15 against counter-rotation after it has been rocked to the position of Figure 11, 13 or 14. To this end the arm 122 of the lever 44 has an edge 136 extending in such direction relatively to the fulcrum of the lever 118 and clearly indicated in Figure 12, 20 that said lever 118, if it is caused to be rocked by unlatching of the bar 113, may correspondingly rock the cross-bar lever 44. At the end of this rotation of the two levers 44, 118, the pin 121 of lever 118 arrives opposite a scooped-out 25 portion 137 of said edge 136. A point or hump 138, at the intersection of the edge 136 and its scooped-out portion 137, affords such point of contact with the pin 121 as the lever 44 reaches said pin after the latter has already been thrust 30 out, as aforesaid, that the lever 44 is rocked counterclockwise while the cross-bar 45 is completing its advance movement.

As indicated in Figure 11, said point or hump 138 approaches and makes contact with the pin 35 121 on the dot-and-dash line 139. In the ensuing rocking of the lever 44 to the position shown in Figure 11, 13 or 14, as the point or hump 138 is thus arrested while the cross-bar completes its 40 advance, it will be seen that the line of reaction afforded by the lever 118 is to be substantially through or on a favorable side of the fulcrum-center of said lever, and hence there is substantially no tendency to rock said lever contrariwise, and therefore there is substantially no tendency 45 to relatch the bar 113. As the lever thus, in the latter case, is rocked to the position shown in Figure 11, the scooped-out portion 137 settles against the pin 121. Since said portion 137 may, at its final point of contact with the pin 121, be 50 substantially perpendicular to the aforesaid line of reaction through the fulcrum-center of the lever 118, as is clearly indicated in Figure 11, the lever 44 is also secured against counter-rotation after it reaches said position, and hence there is 55 no tendency to rebound of the register-bar, even when said bar receives an extra advance for carrying.

The stop-bars 113 are spaced laterally and guided at their forward ends by a slotted transverse bar 140, which may also have slots 141, in which the front portions of the register-bars 21 are guided. The stop-bars 113 are notched at their front ends to form an upper branch 113^a which is received by a slot in said transverse bar 140 and a lower branch 113^b which underlies said transverse bar to limit the upward movement of the forward end of a stop-bar 113. Said register-bars may be guided at their rear portions in slotted transverse plates 142, secured to the cross-member 99 of the framework. Said transverse bar 140 may be retained between the fixed plates 97, which retain the computing-wheel frame 93 against lateral displacement. Each pair of said fixed plates may have rearward extensions 143, 70 between the ends of which may be retained the 75

fixed fulcrum-rod 118 and abutment-rods 113 of the levers 118.

Each of a pair of said fixed plates 97 may have a slot 144, the opposite slots of the pair of plates serving to retain the latch-bar 115 whose ends 5 may be guided in said slots, as indicated in Figures 5 and 8. The shifting of said bar back and forth in said slots 144 is effective not only to bring the register-bar stops 112 into and out of their stopping positions, as aforesaid, but the forward shifting of said latch-bar 115 is also effective to cause the relatching of those stop-bars 113 which have been released. With the position of the parts as seen in Figure 11, 13 or 14, in which the released bars 113 are held by abutment of their levers 118 against the rod 123, it will be evident that shifting of the latch-bar 115 forward, that is, toward the left, to the position indicated in Figure 1 or 10, is effective to relatch the released bars. 20

All of the latch-bars 115 of the several registers are thus shifted back and forth simultaneously, and, to this end, are connected to a universal bar 147, which extends across the machine to span the several registers, as shown in Figures 25 4 and 5, the ends of said bar 147 slightly overlapping the outer side plates 97 of the first and last registers. Movement of the universal bar 147 back and forth is transmitted from the cross-shaft 52, which, as previously explained, has a 30 reciprocatory rotation, resulting from its connection with the general-operator racks 48. To move the universal bar 147 back and forth without skewing, it is engaged at two widely-spaced places along its length by a pair of slides 148, 35 which may be shaped as best seen in Figures 3, 5 and 9. The forward end of each slide 148 has a slot 149 which slidably fits a block 150, located and riveted within a slot 151, cut in a post 152 upstanding from the cross-member 98 of the 40 framework and secured to said cross-member by a screw 154, Figure 3. The sides of the slot 151 retain the forward end of the slide 148 laterally, while the block 150 cooperating with the slot 149 in said slide retains the forward end of said slide 45 vertically. The rear end of the slide 148 has a slot 153 which slidably fits a rectangular block 155, which is provided with a hole for a running fit on the cross-shaft 52.

For enabling the cross-shaft 52 to reciprocate 50 the slides 148, there is fastened to said shaft two cams 156, one cam being adjacent each slide 148. There is secured to each slide 148 a closure-plate 157, having a slot 158. Said closure-plate is secured to its slide 148, by screws 159, on the side 55 opposite to which the cam 156 is disposed. There are on each slide 148 a front cam-roll 160 and a rear cam-roll 161, the former being directly mounted on said slide on a headed stud 162, and the latter roll 161 being mounted on the closure-plate 157 by a headed stud 163. 60

The front roll 160 has an outer flange 164, which may bear against the side of the cam 156 to co-operate with the closure-plate 157 in retaining the slide laterally. For such lateral retention of the slide, the top and bottom edges of the slot 158 of the closure-plate overlap the top and bottom edges of the slot 153 in the slide 148, so that said closure-plate bears on the side of the block 155 which in turn bears on one side of the cam 156 which thus retains said slide laterally, the roll-flange 164 bearing on the other side of said cam. 65

For coupling the slide 148 with the universal bar 147, each slide 148 may have a notch 165. 70 75

which includes at its forward side a tongue 166, which may overlap and underlie the forward edge of the universal bar, and thereby serve to retain the latter at said forward edge. For easy assembling of the parts, the rearward side 165^a of the notch 165 is spaced from the rearward edge of the universal bar, the latter being secured at said rearward edge, however, by means of a block 167 formed as best seen in Figures 3 and 5, said block 10 including a forwardly-projecting tongue 168 which overlaps and underlies the rearward edge of said universal bar. The block 167 is slotted at 169 to embrace the sides of the slide 148, and close the gap between the rearward side 165^a of the 15 notch 165 and the universal bar 147, said block being secured in place by a screw 170.

Connection is made between each latch-bar 115 and the universal bar 147 by means of a pair of links 171 engaging the latch-bar 115 near its 20 ends, and being disposed, therefore, adjacent the fixed plates 97 which support said latch-bar at its ends, as aforesaid, by means of the slots 144. Each latch-bar 115 may, as best seen in Figure 25 7, have at each end a notch 172 to form with a notch 173 in the link 171 an interlocking joint connecting said latch-bar 115 and link 171. The rearward end of each link has a slot 174 which slidably fits a stud 175 projecting from the inner side of the adjacent fixed plate 97. Thus, by 30 means of said slots 174, studs 175 and the slots 144, the latch-bar 115 and its pair of links 171 are guided for back-and-forth movement and are wholly supported by the register fixed plates 97. For connection with the universal bar 147, each 35 link 171 has a notch 176, Figure 7, the front and rear sides of which may, as seen in Figure 5, embrace said universal bar. Each latch-bar may also carry an anchor-plate 177, having perforations for attaching the ends of the springs 114 40 that pull the stop-bars 113 forward as they are unlatched. In order that the pull of said springs 114 may have a downward component, the anchor-plate 177 is somewhat below the spring-ends attached to said stop-bars 113, said downward component of the spring-pull serving to 45 pull the forward end of the stop-bar down when the latch-bar 115 is moved forwardly, and thereby causing the stop-bar to become relatched. For thus positioning the anchor-plate 177, it is 50 spaced from the latch-bar 115 by collars 178, and is secured by screws 179.

Means to ensure positive relatching of the stop-bars 113, and designed to supplement the downward pull of the springs 114, include, for 55 each register and the set of stop-bars 113 therein, a swingable bail 180, having side arms 181, whereby said bail may be pivoted to the inner sides of a pair of fixed plates 97, by pivot-screws 182, threaded into said fixed plates. Said bail 180, extending transversely of the several register-bars 21 and stop-bars 113 of the register, is provided with slots 183, to clear said register-bars and afford prongs, the lower ends of which, reaching downwardly between the register-bars, 60 may engage and push against the top edges of the stop-bars 113. It will be seen that if said bail 180 is pressed downwardly after the latch-bar 115 has been moved forwardly for relatching the stop-bars 113, each stop-bar will be positively urged down, to ensure that the latching edge 116 65 of each stop-bar 113 will be properly caught by said latching bar 115. For imparting such downward movement to the bail 180, the right arm 181 of each bail is extended rearwardly to include a lug 184, which may be engaged by suit-

able means to effect the depression of said bail 180. Such means may be formed on a cross-shaft 185, in the form of teeth 186, which, in a revolution of said shaft, pass over and displace said lug 184, with a consequent depression of 5 the bail 180. Said teeth may be separately inserted in the cross-shaft 185, there being one tooth for each register, each tooth having a stem 188, which is received by a transverse hole in the shaft 185, and is secured by a nut 189, 10 which may be countersunk below the surface of said shaft. The shaft 185 receives a complete revolution during a computing-machine cycle to fulfill operation of means (not shown) for controlling other operations of the computing mechanism, said complete revolution being derived 15 from the reciprocatory motions of the cross-shaft 52 and left-hand rack 46.

To this end, the cross-shaft 52 is provided with an additional sector 190, which may engage 20 a sector 191 loose on the shaft 185. Another sector 192, also loose on said shaft, is coupled to the left rack 46 by an intermediate gear 193, Figure 4. A clutch-device 194, disposed between the sectors 191 and 192, is keyed to the shaft 185 25 and is arranged to receive from the opposite rotations of said sectors 191 and 192 one continuous rotation as the cross-shaft 52 and rack 46 are reciprocated once in a computing-machine cycle. Details of the construction of said clutch-device 194 and its operation with respect to the sectors 191 and 192 are fully set forth in my original application, Serial No. 324,353. The sector 191 is retained by a collar 202, fastened to the cross-shaft 185, the latter being journaled in 30 the side members 41 of the framework. Inasmuch as the bail 180 is depressed when the latch-bar 115 is in its forward position, restoration of said bail may be effected by the rearward movement of said latch-bar 115. To this end, 40 the left arm 181 of said bail has a downward and rearward extension 203, whose lower end, see Figure 10, is in the path of the latch-bar 115 when said latch-bar is to be moved rearwardly. Rearward movement of said latch-bar 115 will 45 therefore cause upward displacement of the bail 180 as seen in Figure 11. While the latch-bar 115 is in said rearward position, the bail 180 is held up and so cannot interfere with upward movement of the stop-bars 113, such upward 50 movement taking place whenever a carrying lever 126 is operated.

The cross-shafts 52 and 185 and the general-operator cross-bar 45 may be supported at their middle portions by a transverse bar 196, secured 55 to and fastened to the front and rear cross-members 98, 99 of the framework. The general-operator cross-bar 45 may bear directly upon the top of said transverse bar 196. To enable said bar 196 to support the cross-shafts 52 and 185, 60 each of the latter is provided with a grooved collar 197, which may have a running fit on its shaft, and one flange of which may bear upon the upper edge of an angle-piece 198, secured to and extending upwardly from the transverse 65 bar 196. The grooves of said collars 197 receive slots 199^a formed in a plate 199, which is attached to the upstanding side of the angle-piece 198 by screws 200. The plate 199 and grooved collar 197 constitute middle bearings for the shafts 52, 70 185, which may be easily dismantled or reassembled to facilitate removal or installation of either shaft 52 or 185. It will further be noted that the arrangement of the slides 148 and of the mounting and operating means therefore is also con- 75

dutive to easy assembly and disassembling of the parts. Furthermore, any register may be easily removed when the screws 281, which secure it to the cross-member 98, Figure 10, are removed.

- 5 The bar 147 may be retained against endwise displacement by two pins 147^a projecting upwardly therefrom and abutting the sides of the transverse bar 196.

The contours of the cams 156 may be so arranged that the latch-bars 115 and the bars 118, the latter having the register-bar stops 112, are shifted forwardly gradually, but soon enough to bring the stops 112 into effective position before a register-bar reaches the end of its advance movement, and similarly the return of the latch-bar 115 is also effected gradually through said arrangement of the contours of the cams 156, the return of the latch-bar 115, and consequently of the bars 118, not commencing, however, any sooner than say, the time at which the returning cross-bar 45 picks up the farthermost advanced register-bar.

Alignment and location of the teeth of the computing-wheel pinions 89 may be secured by individual spring-pressed detents 204, which fit the tooth-spaces of said computing-wheel pinions 89. Said detents 204 may be swingably mounted and spaced on the shaft or cross-member 85 and their springs 204a may be light enough in comparison with the springs 114 so as not to unduly impede the "carrying" force of said latter springs.

As an illustration of the operation of the computing mechanism, consider the following computing example, in addition:

35

$$\begin{array}{r}
 22 \\
 + 8 \\
 \hline
 30
 \end{array}$$

The operator first sees that the computing mechanism is conditioned for addition. The tappet 31 and a tabulating stop 285 having been properly set in relation to the work-sheet zone in which the first item "22" is to be typed, the operator presses the appropriate denominational tabulating key (not shown), and thereby, through connections not shown, raises the corresponding denominational stop 206 to set the typewriter-carriage 14 at the "tens" column of said zone. The item "22" is then typed on the work-sheet by operation of the numeral-keys 10, and during this operation the "2" index-pins 22 are caused to be set in the "tens" and "units" register-bars 21 of whatever register the tappet 31 is set for, it being understood that if only one tappet 31 is set only one set of register-bars will be indexed, and that by setting two tappets 31, one for one register and one for another, accumulation may be effected in two registers. The indexing of the "2" pins in the "tens" and "units" register-bars 21 caused the "0" pins of said bars to be displaced upwardly, by means not shown but described in my aforesaid co-pending application No. 82,226

The number "22" having thus been typed on the work-sheet and corresponding index-pins having been set, the computing mechanism is now ready to be operated for the accumulation of said number in the computing wheels. To this end, the clutch-device of the power-drive is caused to be engaged by retraction of the usual clutch-trip pin, which may be operated by a suitable key and connections, said clutch-device, trip-pin, key, and connections being of the type shown in the aforesaid patent to Hart. Said clutch-device is of such character that the computing-mechanism driver 55 makes one complete

forth-and-back movement and no more, inasmuch as said clutch-device in the normal operation thereof automatically disengages itself at the end of said movement, and the cross-bar 45 therefore makes only one complete forth-and-back movement. Similarly, if the power-drive shown in Figures 2, 15 and 16 be employed, the roller 13 of said drive makes only one revolution and no more, starting from and ending in the position shown in Figure 16.

In the initial portion of the forward stroke of the cross-bar 45, the computing-wheel pinions 88 are caused, by the rocking of the shaft 102, to drop into direct engagement with the register-bar racks 80. As the cross-bar 45 proceeds further in its advance stroke the "tens" and "units" register-bar-engaging fingers 43 on said cross-bar engage the depressed "2" index-pins of the tens and units register-bars which are thereupon advanced two unit-spaces and the tens and units computing wheels 20 are also rotated clockwise two unit-spaces. Before the rack-engaging fingers 43 engaged the depressed "2" pins, the register-bar stops 112 on bars 113 were caused, by the rearward movement of the latch-bar 115, effected by its operating connections, to be moved rearwardly to the position indicated in Figure 9 or 12, and in which position said stops abut the depressed "2" pins of the fully-advanced register-bars. At the end of the advance of said register-bars, the relative positions of the register-bar stops 112, the register-bar-engaging fingers 43, and the cross-bar 45 in respect to the depressed "2" index-pins, are as indicated in Figure 12, from which it will be seen the advanced register-bars are secured against overthrow and rebound.

The cross-bar 45 having now fully advanced the "tens" and "units" register-bars for accumulation of the number "22", said cross-bar is caused, through the effect of the cam-slot portion 70, Figure 11, or the curved portion 78, Figure 15, to be stationary for an interval of time, this stationary period in the operation of the cross-bar 45 affording time for carrying. No carrying operation, however, takes place during the accumulation of the number "22", it being understood that all the register-wheels were originally set at "0". The cross-bar 45 only commences its return after the roll 65 has reached, in the return movement of racks 46, the bottom of said cam-slot portion 70. Similarly, in the power-drive shown in Figure 15, after passing the curved portion 78 of the cross-bar link 75 the continued revolution of the driving roller 13 causes the cross-bar 45 to be returned.

In the initial portion of the return stroke of the cross-bar 45, the computing wheels are caused, by reverse rocking of the shaft 103, to be disengaged from the register-bar racks 80 so as not to be reversed when the cross-bar 45 picks up the register-bars. The cross-bar 45 in its return movement picks up the advanced register-bars by engaging the projections 195 thereof, and, with the co-operation of the spring-device 42, returns them fully to their normal positions, as seen in Figure 1. The cross-bar 45 itself does not move back far enough to effect the full return of the register-bars. Said spring-device 42 completes the return of said register-bars in order to leave a gap 181 (Figure 10), which affords sufficient room for the seriatim advance of the register-bars for indexing of the pins 22. During the return stroke of the cross-bar 45 and its operating train, including the cross-shaft 52, the 75

register-bar-stops 112 on bars 113 are moved forwardly again by the advance of the latch-bar 115 effected through its described operating connections with said shaft 52 to leave room between 5 the "0" pins and said stops for the aforesaid sieriatim advance of the register-bars for pin-setting.

Near the end of the cross-bar 45 return movement, pin-restoring bails not shown, but de- 10 scribed in my original application No. 324,353, are operated to effect restoration of the "2" pins of the "tens" and "units" register-bars by resetting the "0" pins of said register-bars.

After an accumulating cycle of the mechanism 15 for the item "22" is thus completed, the typewriter-carriage 14 being returned either before or after said cycle and the platen line-spaced, the next number "8" is typed on the work-sheet after tabulating said carriage 14 to the units column. 20 The "8" pin will thereby be set in the "units" register-bar with a corresponding restoration of the "0" pin of said register-bar, and the clutch-device of the power-drive is tripped to again operate the mechanism to accumulate "8". During 25 this accumulating operation, the "units" register-bar advances eight spaces, thereby revolving the "units" computing wheel also eight spaces clockwise, and causing it to pass the carrying point, inasmuch as it previously registered "2" 30 and now registers "0". As the "units" wheel so passes the carrying point, its carrying tooth 125 rocks the "units" carrying lever 126 and releases the corresponding stop-bar 113 to effect a forward advance of the register-bar-engaging finger 35 43 for the "tens" register-bar which is thus advanced one unit-space. The "tens" wheel therefore, instead of showing "2", now shows "3". In this particular example, the carrying tooth 125 of the units wheel released the stop-bar 113 as 40 the units register-bar was moving through its last unit-space of movement, so that the carrying advance of the "tens" register-bar is probably effected by the power of the spring 114 of the released stop-bar 113, the actual carrying advance 45 of the "tens" register-bar probably taking place while the cross-bar 45 is in its stationary period.

During the return stroke of the cross-bar 45 and the accompanying counterclockwise rotation of the cross-shaft 52, all the stop-bars 113, 50 except the one which was released for carrying and whose lever 118 therefore already abuts the rod 123, are moved forwardly again by the forward movement of the latch-bar 115, connected to said cross-shaft 52, said latch-bar passing 55 slightly beyond the latching edge 116 of the released stop-bar, and thereby causing the released stop-bar to be latched again, as indicated in Figure 1. Similarly the latch-bar 115 also passes, it may be noted, slightly beyond the latching 60 edges 116 of the other bars 113, after the levers 118 of said other bars in their forward movement finally abut said rod 123. In the relatching of the bars 113 the bails 180 co-operate with the springs 114 in forcing the bars downward, so 65 that the latching edges 116 are sure to be caught by the latch-bar 115 when the latter moves rearwardly in a succeeding cycle. As best seen in Figure 10, the bails 180 are down when the machine is at rest in its normal position, the several 70 bail-actuating teeth 186 being then over the lugs 184 of their respective bails. This locks the carrying bars 113 against accidental unlatching while the machine is at rest. Aside from the 75 release and restoration of a stop-bar 113 and its related parts for carrying, the operations of the

mechanism are the same for the accumulation of "8" as were the operations for the accumulation of "22".

In the subtractive computing example

$$\begin{array}{r} 10 \\ -1 \\ \hline 9 \end{array}$$

5

"10" is first typed and indexed in the "tens" and "units" register-bars, and the computing mechanism is operated to accumulate "10" as aforesaid. The "1" pin in the "tens" register-bar, which, it may be noted, happens to be the only pin indexed, is restored at the end of the accumulating operation by resetting of the "0" index-pin. The "1" to be subtracted is now typed (the carriage having been returned and the platen line-spaced), and correspondingly the "1" index-pin of the units register-bar is set, it being noted that the pin which is set always has the same value as the operated numeral-key, irrespective of whether the item is to be added or subtracted. It may also be noted that in subtraction the zero-pin of a register-bar is also, as in addition, restored by the setting of a higher pin in said bar. 10 15 20 25

In the accumulating operation of the computing mechanism which is now to take place, the computing wheels must be rotated reversely or counterclockwise in order that the "1" may be 30 subtracted. Before a computing cycle is initiated therefore by engagement of the clutch-device of the power-drive, a subtraction-key (not shown) must be first pressed in. By pressing in the subtraction-key, mechanism not shown, but of the 35 type shown in my original application No. 324,353, is conditioned so as to be effective during the computing-machine cycle to shift the computing-wheel frame 93 rearwardly before the register-bars advance, and then forwardly again before 40 the register-bars return, such rearward and forward shifting of said frame 93 causing the computing wheels 20 to engage the intermediate pinions 91 before the register-bars advance and to be disengaged before said register-bars are returned. 45 The rock-shaft 103 remains stationary during the subtractive accumulating operation.

With the computing wheels 20 moved rearwardly into engagement with the intermediate pinions 91, the forward movement of any pin-bar 50 21 causes its computing wheel to be rotated counterclockwise. The "units" wheel which registers "0" is therefore rotated one space counterclockwise from said "0" position to the "9" position, and thus the carrying tooth 125 of said 55 "units" wheel displaces its carrying lever 126, causing the corresponding bar 113, which extends to the "tens" register-bar to be released, with the result that said "tens" register-bar advances one 60 unit-step forwardly. Thereby the "tens" wheel, driven through its intermediate pinion 91, is rotated counterclockwise one step or from "1" which it previously registered to "0", and the computing wheels as a whole now indicate "9", 65 which is the correct result of the above subtractive computing example.

Except for the reversed rotation of the computing wheels caused by their engagement and disengagement with the intermediate pinions 91 instead of with the register-bar racks 90, the accumulating operation of the mechanism and the preparatory indexing of the pins 22 are the same for subtracting a number as for adding a number, that is to say, the operation of the carrying 70 75 75

trains is the same in both cases, and the restoration of the index-pins, by resetting all "0" pins, is also the same in both cases.

At the end of a subtractive computation the mechanism may be restored to its normal additive condition by releasing the subtraction-key, whereupon the mechanism, mentioned as aforesaid as being disclosed in my original application No. 324,353, is conditioned to rock the shaft 103 during an additive computing-machine cycle.

Variations may be resorted to within the scope of the invention, and portions of the improvements may be used without others.

Having thus described my invention, I claim:

15 1. In a computing machine, a plurality of register-wheels, reciprocatable index bars to actuate the same, extents according to the number indexed therein, a general operator to actuate the bars, and having means actuatable whereby an individual index bar is actuated an extra carrying step, and carry-over means, including a pivoted lever controlled by a wheel for interposal into the path of said actuatable means on the general operator, to thereby cause said actuatable 20 means to be actuated to move an index bar one carrying step in addition to the steps indexed in said bar.

2. In a computing machine, a plurality of register-wheels, indexable reciprocatable pin-bars to actuate the same, extents according to the number indexed therein, adjustable pins on each bar, a general operator to engage the indexed pins to actuate the bars, a member on the operator for engaging the adjusted pin of a bar, said member movable relatively to said operator, and carry-over means, including a member releasable by a wheel from a retracted position to engage said movable member and thereby cause said relative movement of the latter to advance 40 said bar for one carrying step in addition to the steps indexed in said bar.

3. In a computing machine, the combination with a plurality of register-wheels, of reciprocatory pin-bars to actuate said wheels according to the pin set therein, a general operator for the pin-bars, each pin-bar having a normally set zero-pin restorable by the setting of a higher pin into the path of the general operator, individually-movable stops for engaging the set pins at the end of the advance movement of the pin-bars, carry-over means co-operative with the general operator and the zero-pin or other set pin of a bar to advance said bar a unit step for carrying, said stops being normally retracted from stopping position to permit a slight advance of the pin-bars for a certain pin-setting operation, and means operative during advance of the general operator to shift said stops to effective position before the advance of the pin-bars is completed, 60 said carry-over means being effective under control of a wheel to again cause a retraction of the stop corresponding to the pin-bar controlled by said carry-over means to permit an extra carrying step of said pin-bar, said shifting means also 65 being reversely effective to restore all of the stops to their original retracted positions as before said advance of the general operator.

4. In a computing machine having a plurality of register-wheels, each wheel having a carry-over tooth, reciprocatable wheel-rotating index bars, individually-settable pins for each bar, and a general operator to reciprocate said bars according to the set pins, in combination with an auxiliary travel-controlling means for said 75 bars, including a device associated with the

general operator for engaging the set pin of a bar, a stationarily pivoted lever rockable to a position for engaging and thereby advancing said pin-engaging device relatively to said general operator at the advance of the latter, and means whereby the carry-over tooth of the wheel of next lower denomination to said bar may rock said lever to said position to effect an additional carry-over step of said bar.

5. In a computing machine having a plurality of register-wheels, each wheel having a carry-over tooth, the combination of reciprocatable wheel-rotating index bars, individually-settable pins for each bar, a general operator to engage the pins when set and actuate their respective bars, and additional travel-controlling means for said bars, including a device carried along with the general operator for engaging the set pin of a bar, a stationarily pivoted lever rockable to a position to engage and thereby advance said pin-engaging device from a retracted position relative to said general operator at the advance of said general operator, a latchable arm connected to said stationarily pivoted lever, a latch-member to normally hold said arm to keep said lever in inoperative position, and means responsive to a tooth of the wheel of next lower denomination to said bar to release said arm from the latch-member to thereby effect said movement of the pin-engaging device relative to the general 30 operator.

6. In a computing machine having a plurality of register-wheels, each wheel having a carry-over tooth, the combination of reciprocatable wheel-rotating index bars, individually-settable pins for each bar, a general operator to engage the pins when set and actuate their respective bars, and additional travel-controlling means for said bars, including a device pivoted to the general operator for engaging the set pin of a bar, a stationarily pivoted lever rockable to a position to engage and in turn rock said pin-engaging device at the end of the advance of said general operator, a latchable arm connected to said stationarily pivoted lever, a latch-member to hold said arm and keep said stationarily pivoted lever inoperative, and a pivoted lever responsive to a carry-over tooth for the wheel of next lower denomination to said bar to release said arm, to thereby effect said rocking of said pin-engaging device for advancing said bar an extra step.

7. In a computing machine having a plurality of register-wheels, each wheel having a carry-over tooth, the combination with reciprocatable wheel-rotating bars, individually-settable pins for each bar, for controlling, at will, the distances traveled by said bars, and a general operator to engage the pins when set and actuate their respective bars, of additional travel-controlling means for said bars, including a shiftable device carried by the general operator for engaging the set pin of a bar, a stationarily pivoted lever rockable to a position to engage and move said pin-engaging device at the end of the advance of said general operator, a latchable arm connected to said lever and constituting a stop limiting the throw of said bar, a latch-member to hold said arm and keep said lever inoperative, and means responsive to a tooth of the wheel of next lower denomination to said bar to release said arm, to thereby effect movement of said pin-engaging device relative to said general operator for advancing said bar an extra step.

8. In a computing machine having a plurality of register-wheels, each wheel having a carry-

over tooth, the combination with reciprocatable wheel-rotating index bars, and a general operator to actuate the bars, of additional travel-controlling means for said bars, including a movable device associated with the general operator for engaging an index bar, a stationarily pivoted lever rockable to a position to engage and move said bar-engaging device relatively to the general operator at the advance of the latter, a latchable 10 arm connected to said lever and constituting a stop, limiting the throw of said bar in two positions, a latch-member to hold said arm and keep said lever inoperative, and means responsive to a tooth of the wheel of next lower denomination 15 to said bar to release said arm from the latch-member, to thereby effect the movement of said bar-engaging device relatively to the general operator for advancing said bar an extra step.

9. In a computing machine having a plurality 20 of register-wheels, each wheel having a carry-over tooth, the combination with reciprocatable wheel-rotating index bars, and a general operator to actuate the bars, of additional travel-controlling means for said bars, including a device 25 movable along with the general operator for engaging an index bar, a pivoted lever to engage and move said bar-engaging device relatively to the general operator from a retracted position at the end of the advance of the general operator, 30 a latchable arm connected to said lever, a power-driven latch-member to hold said arm and keep said lever in inoperative position, and means responsive to a tooth of the wheel of next lower denomination to said bar to release said arm 35 from the latch-member to effect movement of said bar-engaging device relatively to the general operator for advancing said bar an extra step, said power-driven latch-member movable to effect the relatching of said arm and to return said 40 lever to inoperative position.

10. In a computing machine, a plurality of 45 totalizing wheels, indexable reciprocatable denominational racks to actuate the same, for extents according to the numbers indexed therein, adjustable index-pins on each rack, a reciprocatable general operator to engage the indexed pins to advance the racks for rotating the totalizing wheels, and a carry-over mechanism including a pivoted rocker on the operator for engaging 50 the adjusted pin of a rack, said rocker being movable along with said operator, a normally retracted member projectable to engage and rock said pivoted rocker near the end of the rack-advancing stroke of the general operator to thereby 55 advance said rack for one carrying step in addition to the steps indexed in said rack, and means whereby, at every carry-over step of the wheel of next lower denomination to said rack, said retracted member is projected.

60 11. In a computing machine, a plurality of totalizing wheels, indexable denominational racks for rotating the totalizing wheels, and a reciprocatory general operator to drive the indexed racks, in combination with a carry-over train, normally 65 latched in inoperative position, carry-over-control means enabling one of said wheels to trip said carry-over train into operative carry-over position at each carrying step of said wheel, and a member reciprocable along with said general 70 operator and displaceable relatively thereto, said member engaging with said operatively positioned carry-over train as the general operator nears the end of its rack-advancing stroke, and being thereby displaced to drive the rack for the wheel 75 of next higher denomination to said one wheel

a carry-over step in addition to those indexed therein.

12. In a computing machine, a plurality of 5 register-wheels, indexable racks for rotating the wheels, and a reciprocatory general operator for driving said racks, in combination with a spring-pressed carry-over train normally latched in inoperative position, a carry-over control enabling one of said wheels at its every carry-over step to release said train to operative carry-over position, and a rocker pivoted to, and movable along with, said general operator, said rocker being rockable for driving the rack for the wheel of next higher denomination to said one wheel farther than the general operator, said rocker being arranged to engage with the released carry-over train near or at the end of the general-operator advance and thereby be rocked to drive said rack of next higher denomination a carry-over step in addition to those indexed therein.

20 13. In a computing machine having digit-wheels, the combination of a plurality of reciprocatory indexable drive-racks for said wheels, a general operator for cycling said racks to rotate the digit-wheels, carry-over mechanism including carry-over members projectable from an idle position for controlling extra carrying advances of the racks, means over which said carry-over members are latched in idle position and from which said members may escape individually under control of said wheels for the carrying operations, said latching means being reciprocatable for returning and relatching the escaped carry-over members in timed relation to the cycle, and means acting between the opposite strokes of said reciprocatory latching means to force said latching means and carry-over members into interlocking relation, to thereby ensure the return and relatching of all of said carry-over members, said last means being conditioned during the cycle to permit the escape of said carry-over members but being normally in condition to prevent accidental unlatching and escape of said carry-over members.

30 14. In a computing machine, a plurality of 45 digit-wheels, denominational drive-racks for said digit-wheels, a reciprocatory general operator for said racks, denominational orders of settable digit-elements co-operative with said general operator for driving said racks and digit-wheels 50 different extents, a rack-advancer driven along with said general operator, said rack-advancer being movable also relatively to said general operator and co-operative with a set digit-element of one of said racks for driving said one rack farther than said general operator for carrying, carry-over-control means projectable from a retracted position to a carry-over position to enable and cause said carry-over-control means to act against and thereby displace said rack-advancer 55 relatively to the general operator when the latter is near the end of its rack-advancing stroke, and thereby cause said one rack to be driven a carrying step farther than the general operator, and means whereby the digit-wheel of next lower 60 denomination to said one rack projects said carry-over-control means at every carry-over step of said wheel.

15. In a direct-subtraction key-set computing machine, the combination of a group of 70 digit-wheels having carry-over devices thereon, indexable denominational reciprocating drive-racks, rotative idlers permanently in mesh with said racks to be driven thereby, a general operator for cycling said drive-racks, while the digit 75

- wheels mesh either with said racks or said idlers for rotations in opposite directions, so that the advance movement of the racks will cause the digit-wheels either to add or to subtract, and 5 carry-over mechanism operative to enable any digit-wheel except the highest to cause the rack of next higher denomination to be advanced a step more than said general operator, to thereby carry over to or borrow from the digit-wheel 10 driven by said higher rack, said carry-over mechanism including means enabling any digit-wheel at the carry-over operation to effect the recited rack-advance irrespective of whether the digit-wheels are in the position to mesh with said 15 racks or in the position to mesh with said idlers.
16. In a direct-subtraction key-set computing machine, the combination of a group of digit-wheels having carry-over devices thereon, indexable denominational reciprocating drive-racks, 20 rotative idlers permanently in mesh with said racks to be driven thereby, a general operator for cycling said drive-racks, while said digit-wheels mesh either with said racks or said idlers for rotations in opposite directions, so that the 25 advance movement of the racks will cause the digit-wheels either to add or to subtract, and carry-over mechanism including rack-advancers, one for each rack except the lowest, driven with, and individually displaceable relatively to, the 30 general operator, for extending the rack-advances, and means enabling any digit-wheel except the highest at the carry-over operation to determine such displacement of the rack-advancer for the rack of the digit-wheel of next 35 higher denomination, to thereby cause said higher rack to be advanced a step more than said general operator for carrying over to or borrowing from the digit-wheel driven by said higher rack, said enabling means including provision so as to be operative irrespective of whether the digit-wheels are in the position to mesh with said racks or in the position to mesh with said 40 idlers.
45. 17. In a computing machine, a plurality of rotatable register-wheels having carry-over teeth, indexable denominational racks to rotate the wheels predetermined indexed extents, and a general operator to reciprocate said racks, in combination with an adjustable carry-over determinator, a latch to hold said carry-over determinator in ineffective position, means engaged by the tooth of the wheel of next lower denomination to trip said latch and thereby cause said carry-over determinator to be adjusted to effective position, and rack-projecting means movable along with and relatively to said general operator, said rack-projecting means, near the end of the rack-advancing stroke of the general operator, engaging with said effectively positioned carry-over determinator and being thereby operated to drive said rack beyond the range of general-operator movement, for rotating its wheel one extra unit step.
55. 18. In a direct-subtraction key-set computing machine, the combination of a group of digit-wheels having carry-over devices thereon, indexable denominational reciprocating drive-racks, rotative idlers permanently in mesh with said 60 racks to be driven thereby, a general operator for cycling said drive-racks, while said digit-wheels mesh either with said racks or said idlers for rotations in opposite directions, so that the advance movement of the racks will cause the digit-wheels either to add or to subtract, and carry-over 65 mechanism including, for each digit-wheel except the highest, a rack-advancer which is individual to the rack of next higher denomination and is driven along with, and is displaceable relatively to, said general operator, a carry-over determinator adjustable from an ineffective position to an effective position in which, proximate to the end of the advance-stroke of the general operator, said carry-over determinator engages and displaces said rack-advancer to advance said 70 higher rack a step more than said general operator, to thereby carry over to or borrow from the digit-wheel driven by said higher rack, and means whereby the lower digit-wheel, at its carrying step, effects adjustment of said carry-over determinator to effective position, said means including provision whereby said lower digit-wheel is enabled to effect said adjustment to effect the recited rack-advance, irrespective of whether the digit-wheels are in the position to mesh with said racks or in the position to mesh with said idlers.
75. 19. In a direct-subtraction key-set computing machine, the combination of a group of digit-wheels having carry-over devices thereon, indexable denominational reciprocating drive-racks, rotative idlers permanently in mesh with said racks to be driven thereby, a general operator for cycling said drive-racks, while said digit-wheels mesh either with said racks or said idlers for rotations in opposite directions, so that the advance movement of the racks will cause the digit-wheels either to add or to subtract, and carry-over mechanism including, for each rack except the lowest, a rack-advancer driven with and displaceable relatively to the general operator, for extending the advance of said rack, an adjustable overthrow-preventing stop for said rack, and means enabling the digit-wheel of next lower denomination to determine such displacement of the rack-advancer and effect a correlative adjustment of said stop to thereby cause and permit said rack to be advanced a step more than said general operator, for carrying over to or borrowing from the digit-wheel driven by said rack, said enabling means including provision so as to be operative irrespective of whether the digit-wheels are in the position to mesh with said racks, or in the position to mesh with said idlers.
80. 20. The invention as set forth in claim 18 and including an adjustable rack-overthrow-preventing stop individual to said rack, said stop being correlated to said carry-over determinator, so that, when the latter is respectively in ineffective and effective positions, said stop is positioned to limit any rack-advance which, respectively, does not or does include a carrying step, said correlation of said stop and carry-over determinator providing for appropriate adjustment of the stop under control of said lower digit-wheel irrespective of the recited different positions of the latter.
85. 21. A computing machine having, in combination, a plurality of digit-wheels, each wheel having a carry-over device, denominational drive-racks for said digit-wheels, digit-pins for each drive-rack, said pins being settable for predetermined the distances said racks are to be advanced to rotate the digit-wheels, a reciprocating general operator to co-operate with the set pins for advancing said racks, and carry-over mechanism including for each rack, except the lowest, a spring-pressed carry-over determinator latched normally in inoperative position, means

enabling the carry-over device for the digit-wheel of next lower denomination to said rack to release said latched carry-over determinator for resultant movement to carry-over-determining 5 position, as said lower digit-wheel takes a carry-over step, and a rack-advancing means driven along with said general operator, said rack-advancing means being also movable relatively to said general operator, to coact with the set digit-10 pin for said rack for advancing said rack beyond the general-operator advance, said carry-over determinator being operative, when released, to act upon said rack-advancing means and advance the latter a step ahead of said general operator as said general operator nears the end of 15 its advance stroke, to thereby advance said rack and its digit-wheel an extra unit of distance for carrying.

22. In a direct-subtraction computing machine, the combination of a plurality of digit-wheels, indexable denominational wheel-rotating means, a shift of said wheels, from an idle position, in one or another of two substantially perpendicular directions, to different positions to 20 engage said wheel-rotating means, determining forward or backward rotation of the digit-wheels, a general operator for reciprocating said denominational wheel-rotating means to extents depending on the indexing thereof, a carry-over 25 mechanism, including for each digit-wheel, except the highest, a train extending from said wheel toward the wheel-rotating means of next higher denomination, said train including a member settable to condition said train preparatory to an ensuing carry-over, means enabling 30 said digit-wheel as it takes a carrying step to set up said member irrespective of the direction of shift and resultant position of said digit-wheels, and means co-operative with said general 35 operator and with said carry-over train, to actuate said denominational wheel-rotating means to extents determined partly by the indexing thereof and partly by said carry-over train, the latter being effective when conditioned by said digit-40 wheel for a carry-over operation to cause said wheel-rotating means of next higher denomination to be advanced a carry-over step beyond the advance movement of said general operator.

23. The combination of a plurality of digit-wheels, reciprocatory denominational driving members for said digit-wheels, a shift of said digit-wheels in one or another of substantially perpendicular directions from a normally disengaged position to two positions determining, 50 respectively, forward or backward rotation of said digit-wheels, indexing means for the driving members, a carry-over train for each digit-wheel, except the highest, and extending from said digit-wheel to the driving member of next 55 higher denomination, said train including a member settable to condition said train for a carry-over operation, means enabling said digit-wheel as it takes a carry-over step to set said member, said means including provision so as to 60 be operative irrespective of the direction of shift and resultant position of said digit-wheels, and means cooperative with said indexing means, said driving members and said carry-over train to cause said driving members to drive said digit-65 wheels forwardly or backwardly, to individual extents determined partly by the indexing and partly by the conditioning of the carry-over train.

24. The combination of a plurality of digit-wheels, reciprocatory denominational driving 70 members for said digit-wheels, a shift of said

wheels in one or another of substantially perpendicular directions from a normally disengaged position to two positions determining respectively, forward or backward rotation of said digit-wheels, indexing means for the driving members, a general operator co-operative with said indexing means to drive the digit-wheels forwardly or backwardly, to the extents indexed, a carry-over train for each digit-wheel, except the highest, and extending from said digit-wheel 10 to the driving member of next higher denomination, said train including a member settable to condition said train for a carry-over operation, means enabling said digit-wheel as it takes a carry-over step to set said member, said means 15 including provision so as to be operative irrespective of the direction of shift and resultant position of said digit-wheels, and means co-operative with the carry-over train, when the latter is conditioned for a carry-over operation, to give 20 said higher driving member an additional step of advance and the digit-wheel driven by said higher driving member, an additional step of forward or backward rotation.

25. A direct-subtraction key-set computing 25 machine including, in combination, a plurality of digit-wheels, key-indexable denominational reciprocatory driving racks, idle gears driven by said racks, a general operator for cycling said racks while said digit-wheels mesh either with 30 the racks or with the idle gears, a carry-over train for each digit-wheel, except the highest, and extending therefrom to control the rack of next higher denomination, means operative, irrespective of whether the digit-wheels are positioned to 35 mesh with the racks or with the idle gears, for enabling said digit-wheel as it takes a carry-over step to render the carry-over train effective, and means co-operative with the effective carry-over train for imparting to said rack of next higher 40 denomination an additional step of advance and to the digit-wheel driven by said rack an additional step of either advance or retraction, dependent upon whether the digit-wheels are meshing with the racks or idle gears.

26. A direct-subtraction key-set computing machine including, in combination, a plurality of digit-wheels, key-indexable denominational driving racks, idle gears meshing with the racks and driven thereby, the digit-wheels meshing with 50 either the racks or with the idle gears, so that the advance of the racks may drive the digit-wheels either forwardly or backwardly for addition or subtraction states, and carry-over mechanism including for each digit-wheel, a carry-over train extending from said digit-wheel to control the rack of next higher denomination, said train including a portion conditioned according to the state of the digit-wheels to enable 55 said digit-wheel as it takes a carry-over step to 60 operate said train, the remainder of said train being extraneous to said wheels so as to control the next higher rack, said portion and said remainder of said train being relatively arranged so as to co-operate to control said rack irrespective of the state of the digit-wheels, and means co-operative with said carry-over train for causing an extra step of advance to be imparted to said rack of next higher denomination.

27. In a key-set, direct-subtraction computing 70 machine, the combination of a plurality of digit-wheels, key-indexable reciprocatory denominational racks, idle gears meshing with the racks and driven thereby, the digit-wheels meshing with either the racks or the idle gears, so that the 75

advance of the racks may drive the digit-wheels either forwardly or backwardly for addition or subtraction, a general operator for cycling said racks, and carry-over mechanism including for each digit-wheel, a carry-over train conditionable for causing an extra step of advance to be imparted to the rack of next higher denomination to said digit-wheel, and a lever in the path of a carry-over tooth provided upon said digit-wheel, so as to be rocked by either forward or backward rotation of said digit-wheel as the latter takes a carry-over step, said lever having operative connection to said carry-over train, said operative connection being arranged to be operative upon said carry-over train for a carry-over operation irrespective of whether the digit-wheels mesh with the racks or idlers.

28. In a direct-subtraction key-set computing machine, the combination of a general operator, a set of denominational reciprocatory drive-racks operable by the general operator, key-operated indexing mechanism for predetermining the extents said denominational racks are to be driven by said general operator, idlers connected to the drive-racks to be driven thereby, a plurality of digit-pinions engageable with either the racks or the idlers to cause the advance of said racks by said general operator to effect either additive rotation or opposite, subtractive rotation of said digit-pinions, and carry-over mechanism including for each digit-pinion a carry-over train conditionable for controlling an extra carry-over advance of the rack of next higher denomination to said digit-pinion, means enabling said digit-pinion at its rotation in either direction at a carry-over step to condition said carry-over train, said last means being operative irrespective of the adding or subtracting state of the digit-pinions, and means co-operating with said general operator and with said carry-over train to act directly and simultaneously upon said racks, to drive the digit-pinions individually either forwardly or backwardly to the extents determined individually partly by the indexing and partly by the conditioning of the carry-over train.

29. In a direct-subtraction key-set computing machine, the combination of a general operator, a set of denominational reciprocatory drive-racks operable by the general operator, key-operated indexing mechanism for predetermining the extents said denominational drive-racks are to be driven by said general operator, idlers connected to the drive-racks to be driven thereby, a plurality of digit-pinions engageable with either the racks or the idlers to cause the advance of said racks by said general operator to effect either additive rotation or opposite, subtractive rotation of said digit-pinions, and carry-over mechanism including for each digit-pinion a carry-over train conditionable for controlling an extra carry-over advance of the rack of next higher denomination to said digit-pinion, means enabling said digit-pinion at its rotation in either direction at a carry-over step to condition said carry-over train, said last means being operative irrespective of the adding or subtracting state direction of shift and resultant position of the digit-pinions, and an extra advancing means for said higher rack, said extra advancing means being movable along with and relatively to said general operator, and being normally retracted relatively to the general operator while being moved along with the latter, said rack-advancing means being operative to be advanced a step more than the general operator by engagement with said conditioned carry-over

train, to advance said higher rack an extra step for carrying when the general operator is proximate to the end of its rack-advancing stroke.

30. In a key-set, direct-subtraction computing machine, the combination of a general operator, a set of reciprocatory denominational drive-racks operable thereby, key-operated indexing mechanism for predetermining the extents said drive-racks are to be driven by the general operator, idlers connected to the drive-racks to be driven thereby, a plurality of digit-pinions engageable with either said drive-racks or said idlers, and carry-over mechanism including for each digit-pinion a spring-pressed carry-over train releasable from an ineffective non-carrying position in which it is normally latched, to a position in which said train determines an extra step of advance of the rack of next higher denomination to said digit-pinion, means enabling said digit-pinion at its carry-over step in either direction of rotation to release said carry-over train, said last means being operative irrespective of the adding or subtracting state of the digit-pinions, and means on said general operator cooperative with said released carry-over train to cause said higher rack to be advanced one step more than said general operator.

31. In a direct-subtraction computing machine, the combination of a general operator, a plurality of reciprocatory denominational drive-racks operable thereby, denominational orders of key-settable digit-elements co-operative with the general operator to drive the racks different extents, idlers connected to the drive-racks to be driven thereby, a plurality of digit-pinions engageable with either the drive-racks or the idlers, so that advance of the racks rotates said digit-pinions forwardly or backwardly for addition or subtraction, and a carry-over mechanism including for each digit-pinion and the rack of next higher denomination to said digit-pinion, a rack-advancing device movable along with said general operator, and also movable relatively to said general operator to co-operate with a set digit-element of said higher rack for advancing the latter farther than said general operator, means projectable into the path in which said rack-advancing device moves along with said general operator for displacing said device relatively to the general operator and thereby advancing said higher rack one step more than said general operator when the latter is near the end of its rack-advancing stroke, and means enabling said digit-pinion at its carry-over step to project said projectable means irrespective of whether said digit-pinions mesh with said racks or with said idlers.

32. In a computing machine, the combination of a set of digit-wheels, denominational drive-racks, reciprocable for digit-wheel-rotating advances and return strokes, denominational orders of settable digit-index elements for the denominational drive-racks, rack-operating means co-operating with said index-elements to positively drive said racks in wheel-rotating advances of any numbers of steps indexed by a presetting of said index-elements, said rack-operating means including individual rack-advancers co-operative with said index-elements and individually operable for advancing any denominational rack, except the lowest, beyond its indexed number of steps, and carry-over mechanism controlled by said digit-wheels and co-operative with said rack-operating means and its rack-advancers, and with the index-elements to positively drive

any rack, except the lowest, an extra step, dependent on whether a carry-over step of the digit-wheel of next lower denomination to said rack occurs before the last step of indexed advance of said rack, said carry-over mechanism including provision whereby said carry-over mechanism and the rack-advancer for said rack co-operate to effect the extra step of advance of said rack in the event the carry-over step of 10 said lower digit-wheel occurs during or substantially subsequent to said last step of indexed rack-advance.

33. In a computing machine, the combination of a set of digit-pinions, reciprocal denominational drive-racks therefor, a reciprocating general operator for the drive-racks, denominational orders of settable digit-elements through the medium of which said general operator positively drives said racks in digit-pinion-rotating advances of any number of steps indexed by a presetting of said digit-elements, said general operator including rack-advancers, one for each denominational rack, except the lowest, said rack-advancers being individually movable relatively to the general operator, and carry-over mechanism operative, in consequence of a carry-over-initiating step of rotation of any digit-pinion which occurs before the last step of indexed rack-advance, to enable the general operator to 20 translate its last unit of advance, which corresponds to said last step of indexed rack-advance, into a positively driven advance, relatively to the general operator, of the rack-advancer for the rack of next higher denomination to said digit-wheel, said rack-advancer thereby co-operating with the set digit-element for said higher rack to positively drive said higher rack a step more than its indexed advance, to thereby carry positively from said digit-pinion to the digit-pinion 30 of next higher denomination, said carry-over mechanism including means whereby said rack-advancer is advanced, relatively to the general operator, independently of said last unit of general-operator advance, in the event said carry-over-initiating step of the digit-pinion occurs during or subsequent to said last step of indexed rack-advance.

34. In a computing machine, the combination of two digit-wheels, of successive denominations, reciprocal denominational drive-racks for said digit-wheels, a reciprocating general operator for the drive-racks, settable digit-elements through the medium of which said general operator positively drives said racks in digit-wheel-rotating advances of any number of steps indexed by a presetting of said digit-elements, the last step of any indexed rack-advance coinciding with a corresponding final period of the rack-driving stroke of the general operator, and carry-over mechanism, said carry-over mechanism and general operator including co-operable devices whereby in consequence of the lower digit-wheel taking a carry-over-initiating step of rotation, the rack and digit-wheel of higher denomination 55 are driven two steps instead of one step by the general operator during said final period of the general-operator advance, to effect a carry-over to the higher digit-wheel, or said higher rack and its digit-wheel are caused to be advanced one extra step, substantially in sequence to the indexed advance thereof, to effect said carry-over, depending respectively on whether or not said carry-over-initiating step of rotation of said

lower digit-wheel occurs before said final period of general-operator advance.

35. The invention as set forth in claim 34, including an overthrow-preventing stop-device for said higher rack, controlled by said carry-over mechanism so as to be automatically adjusted to oppose said higher rack both at the end of the non-carrying advance and at the end of the carry-over-step-including advance of said higher rack. 5

36. The combination of a single set of denominational computing pinions, a set of denominational driving devices corporately distinct from said single set of computing pinions, each driving device advanceable to indexed digital extents, said driving devices being differentially connectible with said single set of pinions, so that the advance of said driving devices may drive the computing pinions either forwardly or backwardly, to effect either addition or subtraction, cycling means for advancing said driving devices to 10 rotate the computing pinions, trains of carry-over mechanism co-operating with said driving devices, each carry-over train potentially effective to give its driving device an additional step of 20 advance automatically, and carry-over cams on 25 said computing pinions, said carry-over trains being individually operable by means of said cams, whether said computing pinions are being driven for addition or subtraction.

37. The combination of a single set of denominational computing pinions, a set of denominational drive-racks, a set of idle gears permanently meshing with said drive-racks, each drive-rack being advanceable, with concomitant rotation of its idle gear, to indexed digital extents, said set 30 of computing pinions being meshable either with said drive-racks or with said idle gear, to enable the advance of said drive-racks to rotate the computing pinions either forwardly or backwardly to effect either addition or subtraction, cycling 35 means for so advancing said drive-racks, trains of carry-over mechanism co-operating with said drive-racks, each carry-over train potentially effective to give its drive-rack an additional step of advance automatically, and carry-over cams on 40 said computing pinions, said carry-over trains including provision so as to be operable by means of said cams, whether the computing pinions are 45 adding or subtracting.

38. The combination of a single set of denominational computing pinions, a set of denominational drive-racks, a set of idle gears permanently meshing with said drive-racks, each drive-rack being advanceable, with concomitant rotation of its idle gear, to indexed digital extents, said set 50 of computing pinions being meshable either with said drive-racks or with said idle gears, to enable the advance of said drive-racks to rotate the computing pinions either forwardly or backwardly to effect either addition or subtraction, cycling 55 means for so advancing said drive-racks, trains of carry-over mechanism co-operating with said drive-racks, each carry-over train potentially effective to give its drive-rack an additional step of advance automatically, carry-over cams on said 60 computing pinions, and agents, intermediate said carry-over trains and computing pinions, presented differently in congruence with meshing the computing pinions with said drive-racks or idlers, to enable the carry-over cams to operate said 65 carry-over trains, whether the computing pinions are adding or subtracting. 70
